GAME BOARD

Howard E. Braymiller and Nellie F. Braymiller,
Orchard Park, N. Y.

Application August 1, 1939, Serial No. 287,846

2 Claims. (Cl. 273—131)

Our invention relates in general to game boards, and particularly to that type of board used in games where opposing players have men identified by different colors or otherwise which are initially placed upon fields bearing the same identifying characteristics, having for its object to move one's men from the home area of one of said fields to the home area of an opponent's field. Furthermore, our game board is of the type where men are moved from one area to another over lines in definite predescribed manner and where players may jump their own men or their opponent's men without removing from the board the men which have been jumped.

The principal object of our invention has been to provide a game board of this nature in which all of the men of each player in reaching his opponent's field must pass over or through a restricted area identified by a centrally arranged entry spot which may act as resting place for only one of the men at a time.

Another object has been to provide a board for a game which may be played with interest by a novice, but which is sufficiently scientific to be amusing and interesting to a mature player.

The above objects and advantages have been accomplished by the game board shown in the accompanying drawing, of which:

Fig. 1 is a plan view of our game board;

Fig. 2 is a perspective view of one of the diamond-shaped men used upon the game board; and

Fig. 3 is a fragmentary plan view of a modified form of game board.

Our board 10 has its surface divided into the playing fields, the number and position of which depends upon the number of players for which the board is designed. In the drawing we show the board designed to be played by two or four players, and it is obvious that the board may be designed for any number of players, without departing from the spirit of our invention.

As shown in the drawing, there are four playing fields 11, 12, 13 and 14, arranged preferably in pairs. These fields are preferably diamond-shaped and extend radially from a centrally arranged entry spot 15 to which they are adjacent. Each of the playing fields is preferably of a different color, and for purposes of illustration we have indicated the fields 11, 12, 13 and 14 as being red, green, blue and yellow, respectively. Obviously this selection of colors has nothing to do with the playing of the game, and any other suitable colors may be used.

Across the surface of each of the playing fields there is a plurality of intersecting lines 19 and 20 which are arranged preferably parallel to the sides 21 and 22, and 23 and 24 of the fields respectively. At the points of intersection of these lines with each other and at the points where they terminate at the sides 21, 22, 23 and 24 landing spots 25 and 26 are arranged. The lines 19 and 20 and the bounding lines 21, 22, 23 and 24 indicate the normal paths over which a player may move his men. Extending laterally across each of the diamond-shaped playing fields is a line 27 which is arranged preferably on the minor axis of the field. This line may be used in the playing of the game and will be later described. Parallel to this line is another line 28 which is arranged preferably toward the outer end of the diamond-shaped field and at a point where it will intersect a lateral row of landing spots 26. The area enclosed by this line 28 and by the lines 22 and 24 will hereinafter be referred to as the home area.

Our game is preferably played with a plurality of diamond-shaped men 30, one of which is shown in Fig. 2. The number of these men, for each player, is preferably ten and corresponds to the number of spots 26 within and upon the lines bounding each of the home areas.

So as to identify the spots 26 over each home area, upon which each player initially places his men, from the spots 25 over the remainder of the playing field, the spots 26 are solid color and the spots 25 are preferably open circles. In Fig. 1 we have shown the men placed upon the home areas of two opposing playing fields and in positions to start the game.

The board 10 is preferably provided with a decorative border 31, and it may be otherwise decorated by having a square-shaped area 32 enclosing the inner portions of the diamond-shaped playing fields. This area is bounded preferably by a border 33 which, if desired, may extend around the outer ends of the diamond-shaped fields, forming a border 34.

While we have shown the playing fields of diamond shape, it is obvious that the lines bounding the inner ends thereof may be extended substantially to the outer edges of the board, as shown in Fig. 3, where the board is represented at 35 and the playing fields at 36. Each of these fields is triangular in shape having its base 46 near the edge of the board and its apex meeting and joining the apex of another triangular field at a centrally arranged entry spot 37. In 55 a game board having this modified layout more

men are required than in the other form but the game is played in the same manner as in that form. Interspaced parallel lines 38 and 39 extend from the sides 40 and 41, respectively, of each triangle, being parallel, respectively, with the sides 41 and 40. At the points where these lines intersect and at the points where they terminate at the lines 40, 41 and 46, spots 42 and 43 are provided. A line 44 is provided on the playing field and is preferably parallel with the base line 46 of the triangle which, together with a portion of the lines 40 and 41, enclose the home area of the playing field of this form of invention. This line is arranged across a lateral row of spots 43. The spots 43 over the home area are of solid color, and all of the other spots, over the remainder of the playing field are preferably open circles. A line 45 may also be placed upon each of the triangle-shaped fields at some point between the line 44 and the apex of the field on which certain plays may be made, as hereinafter described.

The game played upon our board may be played by two or four players and as indicated in Fig. 1 we have shown the game prepared for the use of two players. The red player has placed his men 30 upon the solid spots 26 of the home area of his playing field 11, and the blue player has placed his men 30 upon the solid spots 26 of the home area of his playing field 13. In playing the game, it is the ultimate goal of each player to place all his men upon the solid spots 26 of his opponent's home area, and the player who first succeeds in doing this is the winner of the game. In doing so each player may move only forwardly upon the lines 19 and 20 toward the opponent's home area, the exception being that when either player's men rest upon one of the lines 27 or 28 of either playing field he can move that particular man laterally in either direction on either of these lines. Obviously, each player in his turn moves but one spot, except in cases where he jumps another man, either his own or his opponent's. During such jump the man jumped is allowed to remain in his spot and is not removed from the board. As the players approach the inner end of each diamond-shaped playing field, they are brought toward the centrally arranged entry spot 15 over which they must pass in order to get into the opponent's playing field, and finally to his home area. A man placed upon this entry spot may be jumped by his opponent if his men are so positioned that such a play is possible, but a player may not remain on this spot more than one turn. It is a rule of our game that no player may "block" the game at the entry spot 15, thereby making it possible for any player in proper position to pass such spot, either by landing thereon in one play or by

jumping over his opponent's man if it occupies the entry spot. The player who gets his men over this entry spot and who is the first to reach his opponent's home area and place all of his men in the solid spots 26 of such area is the winner of the game.

Obviously, some modifications of our game board as shown and described may be made without departing from the spirit of our invention or the scope of the appended claims, and we do not, therefore, wish to be limited to the exact embodiment herein shown and described, the game board shown being merely the preferred embodiment of the invention.

Having thus described our invention, what we claim is:

1. A game board of the class described having a playing diagram thereon consisting of opposite pairs of diamond-shaped playing fields, the fields being symmetrically arranged about the center of the board with their axes at right angles to each other and having their triangularly-shaped inner ends independently interspaced and meeting and joining only in a one man blocking point constituting the only path of communication between one field and another field, a plurality of interspaced, intersecting lines extending over each playing field, a landing spot at each intersection for positioning a play piece, and each field having a home area with an identification landing spot at each of the intersections of the lines of said area for the initial placement of the play pieces and for the final placement of an opponent's play pieces.
2. A game board of the class described having a playing diagram thereon consisting of opposite pairs of diamond-shaped playing fields, the fields being symmetrically arranged about the center of the board with their axes at right angles to each other and having their triangularly-shaped inner ends independently interspaced and meeting and joining only in a one man blocking point constituting the only path of communication between one field and another field, a plurality of interspaced, intersecting lines extending over each playing field, a landing spot at each intersection for positioning a play piece, each field having a home area with an identification landing spot at each of the intersections of the lines of said area for the initial placement of the play pieces and for the final placement of an opponent's play pieces, and one lateral line bounding one side of the home area on which a player may move on the field in a lateral direction, said lateral line being obliquely arranged with respect to the interspaced lines and passing through a series of points of intersections of said interspaced lines.

HOWARD E. BRAYMILLER.
